CLAIM

The ornamental design for a camera system for monitoring cargo of a trailer, as shown and described.

DESCRIPTION

FIG. 1 is a top perspective view of a camera system for monitoring cargo of a trailer showing our new design;
FIG. 2 is a top view thereof;
FIG. 3 is a side view thereof;
FIG. 4 is a rear view thereof;
FIG. 5 is a front view thereof; and,
FIG. 6 is a bottom view thereof.

The broken lines depict portions of the camera system for monitoring cargo of a trailer in which the design is embodied that form no part of the claimed design.
